Patented Aug. 13, 1957

180,812

APPROACH HORIZON INDICATOR FOR AIRCRAFT

Horst M. Schweighofer and Edgar H. Fritze,
Cedar Rapids, Iowa

Application April 9, 1956, Serial No. 40,976

Term of patent 14 years

(Cl. D52—1)

FIG. 1

FIG 2

Figure 1 is a front view of an approach horizon indicator for aircraft showing our new design, and

Figure 2 is a perspective view of our approach horizon indicator for aircraft.

The essential features of the design reside in the full line portions.

We claim:

The ornamental design for an approach horizon indicator for aircraft, as shown and described.
